Attorney.

UNITED STATES PATENT OFFICE.

JAMES S. BRENNAN, OF ATTLEBORO, MASSACHUSETTS.

ORNAMENTAL PLAQUE.

Application filed July 19, 1924. Serial No. 727,080.

To all whom it may concern:

Be it known that I, JAMES S. BRENNAN, a citizen of the United States, residing at Attleboro, in the county of Bristol and State of Massachusetts, have invented certain new and useful Improvements in Ornamental Plaques, of which the following is a specification.

This invention relates to an improved ornamental plaque of pleasing appearance adapted for use as a memorial or for decorative purposes, and more particularly to the manner of constructing and ornamenting the same whereby the structure may be readily formed of wood or any other suitable material and provided with suitable and appropriate ornamental designs formed from ornamental stones suitably arranged thereon.

One object of the invention is to provide a device of this character which may be readily and easily constructed to present a pleasing and novel appearance, while at the same time embodying various improved structural details such as the arrangement of the ornamental stones and the method of securing the same in place.

Other objects and advantages of the invention relate to various details of construction and novel arrangement of the parts as will be more fully set forth in the detailed description to follow.

Referring to the drawings:

Fig. 1 is a front view of the completed structure.

Fig. 2 is a vertical sectional view of one form which the structure may assume in practice taken along the line 2—2 of Fig. 1 with the parts shown separated.

Fig. 3 is a similar vertical sectional view of a modified form of the invention.

Fig. 4 is a vertical sectional view of the gem holding plate, and,

Fig. 5 is a plan view of a portion of the gem holding plate.

In the embodiment of the invention illustrated in Figs. 1 and 2, 1 designates a central body portion which may be formed of wood or other suitable material, and which is adapted to serve as a support for the ornamental stones. The frame portion 2 comprises upper and lower side members 3 and 4 and end members 5 and 6, each of which is provided with an undercut

groove 7, formed to provide an opening of 55 suitable size to receive the body portion 1 when the members 3, 4, 5 and 6 are secured together to form the frame. The provision of the undercut grooves 7 in the frame members results in providing a border 8 projecting inwardly over the edges of the body portion 1 when the parts are in assembled position. A plurality of ornamental stones are secured to one face of the body portion 1, and when the various 60 parts are in assembled position, these stones are exposed to view within the space surrounded by the border 8 of the frame as shown in Fig. 1 of the drawings. The ornamental stones thus secured to the body 65 portion are preferably of different colors so arranged as to form letters whereby words or legends may be designated thereby.

In the present instance white stones 9 and blue stones 10 are so arranged as to 70 form the word "Mother."

The manner of securing the stones to one face of the body portion will now be described. As shown in the drawings a plurality of gem supporting plates 11, of suitable size to fit within the opening surrounded by the border 8 of the frame, are secured to one face of the body portion 1. Each of the gem supporting plates is provided with a plurality of openings 12 80 formed therein and suitably arranged for the receipt of gem holding cups or settings 13. The settings 13 are each provided with prongs 14 for engaging a stone and each of said settings is secured to the plate 11 85 in a suitable manner as by having the base 15 thereof inserted in one of the openings 12 and bent outwardly to form a flange 16 engaging beneath the supporting plate 11. Thus the settings 13 may be secured to each 90 plate 11 prior to the attachment of the plate to the body portion 1. In the present instance each plate 11 is secured to the body portion 1 by means of specially constructed settings 18, each of which is formed in a 100 manner similar to the settings 13 and similarly provided with prongs 19 for engaging a stone, but differing therefrom in that a brad 20 is inserted within the setting prior to the insertion of the stone 9. In practice the settings 13 are omitted from several of the openings 12 in each plate 11, and after the other settings 13 have been in-

serted and stones secured therein the plate 11 is positioned upon the body portion and settings 18 are forced into the vacant openings 12 in such a manner as to force the several brads 20 into the body portion and thus firmly secure the plate 11 to the body portion 1.

While in the present instance a plurality of plates 11 have been shown as employed 10 for supporting the ornamental stones 9 and 10 in Fig. 1 of the drawings, a single plate may be employed for that purpose, and such single plate may be secured to the body portion 1 after the manner described above or 15 in any other suitable manner.

In the embodiment of the invention shown in Fig. 3 of the drawings, the frame 22 is formed of side and end sections as above described but differs from the frame 1 in that the inwardly extending border is omitted. The central space surrounded by the frame 22 is of uniform cross-section throughout. The central body portion 23 is formed in a manner similar to that of the 20 central body portion 1 shown in Fig. 2 but instead of being bodily removable from the frame is firmly secured thereto in any suitable manner. Supporting plates 11 provided with settings 13 and 18 carrying stones 30 9 and 10 are secured to the body portion 23 after the manner previously described. A filler plate 24 may be inserted to fill the space at the rear of the body portion 23 and give a smooth and finished appearance to the 35 rear surface of the ornamental plaque.

From the above description it will be seen that I have provided a novel arrangement of parts whereby a structure may be readily and easily formed which presents an attractive 40 appearance to the observer, and provides a novel form of ornamentation together with an attractive means for exhibiting words, legends or other devices by a suitable arrangement of stones of different 45 colors.

What I claim is:—

1. An article of the character described comprising a central body portion, a frame surrounding said body portion and extending 50 outwardly therefrom to form a central recess on one side thereof, a plurality of metal plates arranged to fit within said central recess, said plates being each provided with a plurality of openings arranged in 55 symmetrical order relative to the edges of said central recess, gem holding cups secured in the openings in said plates, ornamental stones carried by said cups, and means for securing said plates to said body 60 portion.

2. An article of the character described comprising a central body portion, a frame surrounding said body portion of greater thickness than said body portion, the parts 65 being positioned relative to each other to

form a recess upon one side of the body portion, a plurality of plates fitting within the recess and each provided with a plurality of openings arranged in parallel lines, gem holding cups secured in the openings in said plates, ornamental stones carried by said cups, and means associated with certain of said gem holding cups for securing said plates within the recess.

3. An ornamental article of the character described having a recess formed upon one side thereof, a plurality of plates fitting within said recess and each provided with a plurality of openings formed therein, the openings being arranged in regular order 75 relative to the edges of said recess, gem holding cups each provided with a reduced end portion adapted to be positioned in one of the openings and secured to the corresponding plate, and means for securing the plates 80 in the recess.

4. An ornamental article of the character described provided with a recess formed upon one side thereof and having a raised edge surrounding said recess, a plurality of 90 plates fitting within said recess and each provided with a plurality of openings formed therein the openings being arranged in regular order relative to the edges of said recess, gem holding cups each provided with 95 a reduced end portion adapted to fit within one of the said openings and certain of said cups having the inner ends thereof enlarged after their insertion in the openings to secure the cups against removal from the 100 plates, ornamental stones supported by said cups, and means carried by certain of said gem holding cups for securing the plates within the recess.

5. An ornamental article of the character 105 described provided with a recess formed upon one side thereof and having a raised edge surrounding said recess, a plate fitting within said recess and provided with a plurality of openings formed therein the openings being arranged in regular order relative to the edges of said recess, gem holding cups each provided with a reduced end portion 110 adapted to fit within one of said openings and certain of said cups having the inner ends thereof enlarged after their insertion in the openings to secure the cups against removal from the plate, ornamental stones supported by said cups, and means carried by certain of said cups for securing the plate 115 within the recess.

6. An ornamental article of the character described provided with a recess formed upon one side thereof and having a raised edge surrounding said recess, a plate fitting 120 within said recess and provided with a plurality of openings formed therein the openings being arranged in regular order relative to the edges of said recess, gem holding cups each provided with a reduced end 125

portion adapted to fit within one of said openings and certain of said cups having the inner ends thereof enlarged after their insertion in the openings to secure the cups

5 against removal from the plate, ornamental stones carried by said cups certain of said stones being colored and arranged to form

letters whereby a word or legend may be indicated by the arrangement of the stones, and means carried by certain of said cups 10 for securing the plate within the recess.

In testimony whereof I have affixed my signature.

JAMES S. BRENNAN.
